DESIGN FOR A BACK FOR A BILLFOLD

Aaron Mouldovan, Brooklyn, N. Y.

Application March 17, 1948, Serial No. 145,182

Term of patent 3½ years

(Cl. D87—3)

To all whom it may concern:

Be it known that I Aaron Mouldovan, a citizen of the United States, residing at Brooklyn, New York, in the county of Kings and State of New York, have invented a new, original, and ornamental Design for a Back for a Billfold, of which the following is a specification, reference being had to the accompanying drawing, forming a part thereof:

In the drawing:

Fig. 1 is a top plan view of a back for a billfold, in fully open position, showing my new design; and

Fig. 2 is an edge view of the same looking in the direction of the line 2—2 of Fig. 1.

I claim:

The ornamental design for a back for a billfold, as shown.

AARON MOULDOVAN.
